UNITED STATES PATENT OFFICE.

JOHN DEAN AND SAMUEL P. EMERSON, OF WORCESTER, MASSACHUSETTS.

DESIGN FOR A PHOTOGRAPH-PRESERVER.

Specification forming part of Design No. 1,521, dated February 4, 1862.

To all whom it may concern:

Be it known that we, JOHN DEAN and SAMUEL P. EMERSON, of the city and county of Worcester, State of Massachusetts, have invented or produced an original Design for a Daguerreotype and Photograph Preserver; and we do hereby declare that the following is a full and exact description of the same, reference being had to the annexed drawing, making part of this specification.

The distinguishing feature of our design of an ornamental preserver for daguerreotypes, photographs, and similar pictures consists in a combination of stars and a beading of filigree work, as shown in the drawing herenunto annexed.

In Figure 1 is represented a preserver having a star *a* placed in each corner, with the filigree beading along the edge of the frame, as shown at *b*. Each star has also a setting of scroll or leaf-work extending upon the frame.

We claim—

The ornamental design for a daguerreotype and photograph preserver, substantially as described herein.

JOHN DEAN. [L.S.]
SAM'L P. EMERSON. [L.S.]
